MACHINE FOR FOLDING PAPER OR
OTHER MATERIALS

Reuben Hitchcock, deceased, late of Cleveland, Ohio, by Lawrence Hitchcock, H. Morley Hitchcock, C. W. Hitchcock, Cleveland, and D. B. Meacham, Cincinnati, Ohio, executors, assigns, or to Dexter Folder Company, New York, N. Y., a corporation of New York

Application April 17, 1935, Serial No. 16,825

20 Claims. (Cl. 270—68)

This invention relates to folding machines and more particularly to folding machines of the buckle type that are capable of making folds and cross folds in sheet material fed therethrough.

In the patent to Reuben Hitchcock, No. 1,273,609, granted July 23, 1918, there is disclosed a buckle type folding machine for making folds and cross folds in sheets of paper or the like, and wherein the first fold mechanism comprises relatively displaceable normally horizontal folding devices from any one of which a sheet fed therethrough and folded thereby may, through the provision of a vertically adjustable cross feed mechanism, be delivered directly to a cross fold mechanism disposed vertically or at right angles to the first fold mechanism and adapted for the making of a fold in said sheet at right angles to the fold or folds made therein by the preselected folding device or devices of said first fold mechanism.

The machine shown in said patent, while entirely satisfactory in accomplishing the results for which it is designed, is incapable, particularly between the horizontally and vertically disposed folding mechanisms aforesaid, of cutting or dividing a sheet into separate sections and delivering them one after another, while standing on their lower edges, to the vertical or cross fold mechanism, and it is therefore one object of the present invention to provide an improved buckle type folding machine which will accomplish these results regardless of the particular folding device or devices of the first fold mechanism employed, and regardless of the size of the original sheet and the sections produced therefrom.

Another object of the present invention is to provide a buckle type folding machine which will cut or divide a sheet into separate sections and feed them standing on edge to a folding mechanism at right angles to a similar mechanism from which the original sheet was delivered.

Another object of the present invention is to provide a buckle type folding machine embodying cutting and feeding means capable of receiving sheet material selectively from different parts of one folding mechanism and which will cut or divide the material into separate sections and feed them, while they stand on their lower edges, one after another directly from the preselected part or parts of said folding mechanism to another folding mechanism at right angles thereto.

Another object of the present invention is to provide a buckle type folding machine with feed mechanism which will engage a standing series 55 or plurality of separate sheet sections on both

sides of lower edge portions of each section and feed said sections, while they stand on their lower edges, one after another to a part of said machine or place of delivery for said sections.

Another object of the present invention is to provide a buckle type folding machine with feed mechanism such as above referred to and which, in acting on the standing separate sheet sections, will accelerate movement of the leading section to a part of the machine or place of delivery for 10 said sections.

Another object of the present invention is to provide an improved feed mechanism for folding or other machines, which embodies guide means and opposed roller and ball devices arranged and 15 operated in such relation that separate sheet sections may be fed one after another thereby while standing and supported on their lower edges.

Another object of the present invention is to provide a sheet cutting and feeding unit for use 20 between angularly related folding or other mechanisms and which is adjustable to receive sheet material selectively from different parts of one of the mechanisms, cut the material into separate sections, and feed said sections one after another 25 to the other mechanism.

Another object of the present invention is to provide a sheet cutting and feeding unit of the type aforesaid and wherein the cutting and feeding devices are arranged or mounted for relative 30 adjustment while at the same time being adjustable as a unit with respect to a mechanism from which the sheet is received.

Another object of the present invention is to provide an improved feed unit for use with folding or other machines and which has flared or other suitably formed guides adjustable with respect to each other and with said unit.

These and other objects of the present invention will appear as the following description 40 thereof proceeds, and in order to more clearly understand the inventive idea, reference may be had to the accompanying drawings illustrating two embodiments of said invention.

In said drawings:—

Fig. 1 is a fragmentary vertical longitudinal sectional view of a buckle type folding machine constituting one embodiment of the present invention;

Fig. 2 is an end view, partly in section, of said 50 machine;

Fig. 3 is a top plan view, partly in section, of cross feed and folding mechanisms shown in Fig. 2;

Fig. 4 is a fragmentary vertical longitudinal 55

sectional view of a buckle type folding machine constituting another embodiment of the present invention;

Fig. 5 is a detail view, partly in section, of cross feed mechanism shown in Fig. 4;

Fig. 6 is a fragmentary side elevation of said last mentioned cross feed mechanism; and

Figs. 7 and 8 are detail views of means for driving the cutters and cross feed mechanism shown in Figs. 1, 2 and 4.

Referring to the drawings, wherein like reference characters designate like parts throughout the several views, the embodiment of the invention shown in Figs. 1 and 2 comprises a buckle type folding machine having side frames 5 and 6, a horizontally disposed feed table 7 including driven rollers 8 extending diagonally thereof, a feed roller 9 disposed forwardly of said table, and feed wheels 10 which are located above said feed roller and frictionally driven thereby.

The feed table 7, which is of well known construction, is supported in any suitable manner on and between the side frames 5, 6 at the top and rear thereof, and the rollers 8 are driven by any suitable means in order to feed sheets from a supply thereof to feeding and folding instrumentalities hereinafter described. The feed roller 9 is journalled in suitable bearings on said side frames and said roller is driven by the usual gearing (not shown) generally employed for this purpose. The feed wheels 10 are journalled on a shaft 11 which is mounted in any suitable manner on the side frames 5, 6, and sheets fed one after another by the rollers 8 to the feed roller 9 and feed wheels 10 are delivered thereby in like manner to the aforesaid feeding and folding instrumentalities over an inclined plate 12. Accidental displacement of the sheets upwardly from the plate 12 is prevented by a plate 13 located above the same in spaced parallel relation therewith, and said plates are supported in any suitable manner on the side frames 5 and 6.

Journalled in suitable bearings in brackets 14, 14' (Fig. 2) that are bolted or otherwise suitably secured to side frame 5 is a short shaft 15 which has fixed thereon a pulley 16 that is driven by a belt (not shown) from any suitable source of power. The shaft 15 also has fixed thereon one of the gears of a train thereof indicated at 17 and journalled in any suitable manner on the side frame 5. The gear of train 17 that is fixed on shaft 15 meshes with a gear 18 which is fixed on the top roller 19 of a vertical bank or series of horizontal parallel feeding and folding rollers including said roller 19 and rollers 20, 21, 22, 23 and 24. This vertical bank or series of rollers, and a plurality of parallel horizontal fold plates 25, 26, 27, 28 associated therewith, comprise the first fold mechanism to the rollers 19, 20 of which sheets are fed one after another over the plate 12 by the described means for this purpose.

The first fold mechanism and sheet stops and deflectors (not shown) of well known construction employed therewith, enable one, two, three or four folds to be made in a sheet by feeding, buckling and folding it in a manner well understood in the art and requiring no detailed explanation herein. This first fold mechanism is preferably divided into relatively displaceable sections or folding devices, as disclosed in Hitchcock Patent No. 1,273,609 above referred to. Accordingly, the rollers 23, 24 and the fold plates 27, 28 are journalled and mounted, respectively, on a supplemental frame including side members

29 and 30 that are fixed on a rod 31 journalled in suitable bearings on the side frames 5 and 6.

The rod 31 has fixed thereon bars 32 for swinging the supplemental frame and parts carried thereby into and out of their operative and inoperative position indicated by full and dotted lines, respectively, in Fig. 1 of the drawings. Pins 33 and 34 on the side frames 5, 6 serve to hold the supplemental frame and the parts carried thereby in their operative and inoperative positions, the bars 32 being engaged with said pins after said supplemental frame and parts have been swung to said positions.

The rollers 19, 20, 21, 22 and the fold plates 25, 26 are journalled and mounted, respectively, on the side frames 5, 6, and in the operative position of the supplemental frame and parts carried thereby, these rollers and the rollers 23, 24 are all driven by a train of gears 35 each fixed on one of said rollers. The gears on the rollers 22 and 23 are engaged and disengaged as the supplemental frame and parts carried thereby are moved to their operative and inoperative positions, respectively. Referring now more particularly to Fig. 2 of the drawings, the machine therein shown includes a second or cross fold mechanism of the buckle type the parts of which are disposed vertically or at right angles to the first fold mechanism and mounted on the side frame 6 of said machine. This second or cross fold mechanism is preferably operated and constructed as follows.

Fixed on the short shaft 15 is a bevel gear 36 which meshes with a bevel gear 37 that is fixed on the upper end of a vertical shaft 38 journalled in suitable bearings on brackets 39 and 40 which are bolted or otherwise suitably secured to the side frame 5. The shaft 38 has fixed on the lower end thereof a bevel gear 41 which meshes with a bevel gear 42 that is fixed on a short shaft 43 journalled in suitable bearings on the bracket 40. This short shaft 43 has fixed thereon a spur gear (not shown) which meshes with a similar gear 44 that is fixed on one end of a cross shaft 45 journalled in suitable bearings on bracket 40 and a bracket 46. The bracket 46 is bolted or otherwise suitably secured to the side frame 6. The opposite end of cross shaft 45 has fixed thereon a bevel gear 47 which meshes with a bevel gear 48 that is fixed on a roller 49 disposed vertically at right angles to the rollers of the first fold mechanism. This roller 49 and vertical rollers 50 and 51 parallel therewith and also disposed at right angles to the rollers of the first fold mechanism, are journalled in suitable bearings on the bracket 46 and a bracket 52 that is bolted or otherwise suitably secured to side frame 6.

The roller 49, through the described driving connections therefor with the driven shaft 15, is thus driven from the latter, and the rollers 50 and 51 are driven from roller 49 through a train of gears 53 each fixed on one of said rollers. The second or cross fold mechanism, in addition to the feeding and folding rollers 49, 50, 51, includes a fold plate 54 operatively associated therewith and mounted in any suitable manner on the brackets 46 and 52 to extend vertically or at right angles to the parts of the first fold mechanism. The second or cross fold mechanism is provided with a sheet stop and a deflector (not shown) of well known construction, and when sheet material is fed from the first fold mechanism to said second fold mechanism by means hereinafter described, said second fold

mechanism will, if the deflector is in inoperative position, make a cross fold in said material at right angles to the fold or folds previously made therein by the first fold mechanism. This cross fold results from the feeding, buckling and folding of the sheet material by the cross fold mechanism in a manner well understood in the art and requiring no detail explanation herein. The sheet material may, however, through the use 10 of the deflector of the cross fold mechanism, be fed therethrough without folding thereby, if so desired.

The first fold mechanism and the second fold mechanism have interposed therebetween means 15 for acting upon and feeding sheet material from one to the other of said mechanisms. Said means, in accordance with the present invention, comprises a cutting and feeding unit adjustable to receive sheet material from different relatively 20 displaceable devices of the first fold mechanism and adapted to cut the material into sections and feed them standing on edge one after another directly from the pre-selected folding device or devices of the first fold mechanism to 25 said second or cross fold mechanism. In the embodiment of the invention shown in Figs. 1, 2 and 3, the aforesaid cutting and feeding unit is operated and constructed as follows.

The shaft for the lowermost gear of the train 30 17 has fixed thereon a spur gear 55 which, in the full line position of the parts shown in Figs. 1 and 2 of the drawings, meshes with a similar gear 56 that is fixed on one end of a shaft 57. This shaft 57 is journalled in suitable bearings 35 in blocks 57' that are bolted or otherwise suitably secured on lugs or extensions 58 formed on and projecting upwardly from an upper cross bar 59 of a frame that is indicated broadly at 40 60. This frame 60 includes a lower cross bar 61, and side members 62, 62' the upper ends of which are fitted in suitable openings in the cross bar 59 and rigidly secured thereto in any suitable manner. The lower ends of the side frame members 62, 62' are fitted in suitable openings 45 in the cross bar 61, and said side frame members, with the upper cross bar, are adjustable toward and away from the first fold mechanism and held in adjusted position, through the medium of set screws 63 threaded in the lower 50 cross bar 61 through plates 63' releasably clamped by said screws on the members 62, 62'. The lower cross bar 61 is provided with lugs or ears 64 having suitable openings therein for bushings 65. The cross shaft 45 passes through 55 the bushings 65, supports the frame 60 and parts carried thereby, and provides a horizontal pivot for the frame 60 at the lower end thereof about which said frame and said parts may be swung to their operative and inoperative positions illustrated in full and dotted lines, respectively, in Fig. 1 of the drawings. The cross feed frame 60 and parts carried thereby are held in operative position by a bar 66 pivoted at 67 on said frame and provided with a hook 68 that is engaged over a stud 69 on side frames 5 and 6 and locked on said stud by a wing nut 70 threaded thereon.

The shaft 57 has adjustably mounted thereon at intervals cutters 71, and the gear 56 on said shaft meshes with a gear 72 that is fixed on a shaft 73 having cutters 74 adjustably mounted thereon in cooperative relation with the cutters 71. The shaft 73 is journalled in suitable bearings on blocks 57' which, as previously pointed out, are secured on the lugs or extension 58 of

the upper cross bar 59, and said blocks have bolted or otherwise suitably secured thereto, a guide 75. This guide 75 serves to direct a sheet from rollers of the first fold mechanism to and between the cutters 71, 74 which act to cut said 5 sheets into a series of separate sections 76. The series of separate sheet sections 76 are delivered downwardly into the frame 60 through a guide 77 on the upper cross bar 59 of said frame.

The side members 62, 62' of frame 60 have ad- 10 justably secured thereto, as by set screws 78, flared guides 79, 80 and 81 capable of being nest- 15 ed one within the other as shown in Figs. 4 and 8 as well as being capable of adjustment relatively and with the frame 60. The sheet sections 76, 15 which are formed by the cutters 71, 74, and de- 20 livered therefrom through the guide 77, pass downwardly therefrom through the flared guides 79, 80, 81 and between cross feed devices 82, 83. These cross feed devices are arranged in two 25 opposed rows extending substantially throughout the length of a horizontal guide 84 provided longitudinally thereof with a groove 85. This 30 guide 84 and the cross feed devices 82, 83 which are carried thereby, are adjustable with, and 35 relative to, the frame 60. For this purpose, the guide 84 has bolted or otherwise suitably secured thereto over the side members 62, plates 86 in which are threaded wing screws 87 for releasably 40 clamping said guide to said side members. The 30 sheet sections 76 after passing between the cross feed devices 82, 83 enter the groove 85 of the 45 guide 84, stand therein on their lower edges, and are retained in vertical or standing position by the adjacent flared guide or guides while being 50 fed therethrough laterally of frame 60 to the second or cross fold mechanism by said cross feed devices.

The cross feed devices 82 are comprised by 45 short substantially vertical rollers rounded or otherwise suitably formed at the tops thereof and rotatable about substantially vertical axes provided by shafts 88 which have the rollers fixed thereon and are journalled in suitable bearings on the guide 84 at one side of the groove 85 55 45 therein. The shafts 88 have fixed thereon below the guide 84, small spur gears 89, the hubs 90 of which are secured in any suitable manner on the shafts 88. The gears 89 mesh with idler gears 91 disposed under the guide 84 and rotatable about 50 substantially vertical axes provided by stud screws 92 or the like extending loosely through openings in said idler gears and threaded or otherwise suitably secured on the guide 84 at the under side thereof.

The guide 84 has formed thereon, or suitably 60 secured thereto, a fork 93 in which is journalled a small stud 94 having enlarged upper and lower ends 95 and 96 which engage said fork on opposite sides thereof to hold said stud against displacement vertically with respect thereto. The lower end 96 of the stud 94 has rigidly secured thereto, or formed integrally therewith, a spur gear 97 which meshes with one of the idler gears 91. This spur gear 97 serves to drive the idler 65 gears 91 which, in turn, drive the gears 89, the shafts 88 and the cross feed devices or rollers 82. The gear 97, in turn, is driven by a vertical shaft 98 extending through said gear, the stud 94, and its upper and lower ends 95, 96 and connected 70 therewith by a spline or feather 99 that enables the guide 84 and driven parts thereon to be adjusted vertically on frame 60 without disturbing the described driving connections for said parts with said shaft.

The lower end of shaft 98 is journalled in a suitable bearing 100 on the lower cross bar 61, and the upper end of said shaft is journalled in a suitable bearing 101 formed on an offset portion 102 of the upper cross bar 59. This shaft 98 has fixed thereon above the bearing 101, a bevel gear 103 that meshes with a similar gear 104 fixed on a shaft 105 which, together with said gear serves to drive the shaft 98. The shaft 105 is journalled in suitable bearings on the lugs 58 formed on the upper cross bar 59 of frame 60, and said shaft has fixed thereon a spur gear 106 which meshes with the spur gear 12 on the cutter shaft 73. It will thus appear that when the machine is in operation and the frame 60 and parts carried thereby are in their full line positions shown in Fig. 1 of the drawings, the cutter shafts 57, 73 will be driven through gears 56, 12 from gear 55, and that the rotatable parts on guide 84, in any position of adjustment of the latter on frame 60 will be driven from gear 12 through the described driving connections for the latter with said parts.

The sheet sections 76, as before pointed out, are delivered onto guide 84, between the cross feed devices 82, 83 and feeding of said sections to said guide through the guides 77, 79, 80, 81 is effected by gravity and the action of feed wheels or rollers 107, 108 that are fixed on the cutter shafts 57, 73. The cross feed devices 83 are disposed each opposite one of the cross feed devices or rollers 82 and cooperate therewith to hold the sheet sections 76 in engagement with guide 84 and feed said sections therealong to the second or cross fold mechanism as previously pointed out. For this purpose, the cross feed devices 83 are, in the embodiment of the invention shown in Figs. 1, 2 and 3, comprised by balls or spherical rolling weights mounted and arranged as follows.

The guide 83 has secured thereto at intervals along the same, as by machine screws 109 (Fig. 1) or other suitable fastening means, channel or trough shaped holders 110 in which the spherical cross feed devices 83 are mounted. These holders are disposed each opposite one of the cross feed devices or rollers 82 and are inclined downwardly toward the same so that the spherical devices 83 press downwardly through lower open ends of said holders against the adjacent sides of the lower edge portions of the sheet sections 76 and hold the sheet sections in engagement with the guide and the cross feed devices or rollers 82. The upper ends of the holders 110 are provided with guards 111 for preventing displacement of the devices 83 from said holders through the upper ends thereof. The cross feed devices or rollers 82 engage the sides of the lower edge portions of the sheet sections 76 opposite those engaged by the devices 83 and said devices 82, 83 cooperate to feed said sections one after another in standing position along guide 84, through a vertical guide 112 of the second or cross feed mechanism, and between the rollers 49, 50 of the latter for the making of cross folds in the sections by said mechanism or delivery of the sheet sections therefrom without folding, as desired.

The movement of the leading sheet section, or the one nearest the cross fold mechanism, is preferably accelerated to separate it from the remaining sheet sections a distance sufficient for feeding and folding of said sections, without interference, one after another by said mechanism as they are fed in like manner thereto. For

this purpose, the spherical device or devices 83 engaging said leading sheet section may be slightly heavier than the remaining devices 83 or the latter may be somewhat smaller or made of lighter material in either case such that the device or devices 83 engaging the leading sheet section are heavier than the remaining device or devices 83 and the movement of said section is therefore accelerated as aforesaid.

In the embodiment of the invention shown in Figs. 1, 2 and 3 the operative relation of the parts has been established by swinging the frame 60 and parts carried thereby to their dotted line position illustrated in Fig. 1, swinging the supplemental frame 29, 30 and parts carried thereby from their dotted line positions (Fig. 1) to their full line positions, locking said supplemental frame and last named parts by engaging the bars 32 over pins 33, swinging frame 60 and parts carried thereby to their full line positions (Figs. 1 and 2) wherein gear 56 meshes with the underside of gear 55 (Fig. 7), and locking frame 60 and parts carried thereby in their operative or full line positions (Fig. 1) by engaging the hook 68 of bar 66 over stud 69 and tightening wing nut 70.

In the embodiment of the invention shown in Figs. 4, 5 and 6, the holders 110 for the spherical cross feed devices 83 are provided with trunnions 113 journalled in lugs 114 secured to or formed on the guide 84' the form of which is slightly different from that of the guide 84. In this case, the thin edge portion 115 of guide 84' has threaded therethrough screws 116 which engage the holders 110 and by which the angle 35 thereof with respect to the cross feed devices or rollers 82' may be varied, as desired. These cross feed devices 82', as shown in Figs. 4 and 5 of the drawings, are somewhat larger than the devices 82. The screw or screws 116 for the holder or holders 110 carrying the device or devices 83 that engage the leading sheet section may, for example, be adjusted to increase the angle of said holder or holders, increase the pressure of said device or devices on said sheet section, and thereby accelerate its movement to separate it from the remaining sheet sections and insure orderly feeding and folding of all the sheet sections in sequence. These screws 116 are provided with knobs or handles 117 for turning 50 or adjusting them, and said screws are further provided with lock nuts 118 for retaining them in adjusted position. The adjusting screws 116 further serve to adjust any or all of the holders 110 in order to obtain the necessary or desired 55 action of the spherical devices 83 on the sheet sections.

The construction, arrangement and operation of the parts of the embodiment of the invention shown in Figs. 4, 5 and 6 is otherwise the same 60 as set forth in connection with the first described embodiment of said invention. It is pointed out, however, that as shown in Fig. 4 of the drawings, the supplemental frame 29, 30 and folding devices carried thereby have been swung downwardly to their inoperative position illustrated in full lines, and that the guide 75 and cutters 71, 74 are positioned opposite the rollers 21, 22 to receive the sheet material and produce separate sheet sections 76 that are delivered directly from said cutters and rollers to the second or cross fold mechanism by the described cross feed devices and in the manner previously pointed out.

In order to locate guide 75, cutters 71, 74 and other parts on frame 60 as they are shown in Fig. 75

4, the side frame members 62, 62' are, through the described means for this purpose, adjusted relative to the lower cross bar 61 so that upon swinging frame 60 into operative relation with 5 the non-displaceable parts of the first fold mechanism, guide 75, cutters 11, 14 and the cross feed mechanism will occupy the position shown in full line in Fig. 4 and the gears 55 and 56 will be brought into mesh as shown in Fig. 8 wherein it 10 will be noted that the axis of rotation of gear 56 is above the axis of rotation of gear 55 instead of below it as shown in Figs. 2 and 7.

It will appear from the foregoing that, in addition to the provision of means for producing 15 separate sheet sections and feeding them standing on edge one after another to folding or other mechanisms at right angles to mechanism from which the material for said sections was delivered to said means, the present invention provides 20 cutting devices and cross feed devices assembled as a unit adjustable with respect to relatively displaceable parts of folding or other mechanism in such manner as to receive sheet material from a preselected part or parts thereof, cut the material into separate sections and feed the latter, 25 while in standing position, directly from said part or parts to another mechanism for folding, receiving or otherwise acting on said sections. It will further appear, that the present invention 30 affords a cutting, guiding, and cross feeding mechanism the parts of which are not only adjustable as a unit in the manner aforesaid, but which are also adjustable relative to each other in order to act upon sheets and sheet sections of 35 different sizes.

Two embodiments of the present invention have been illustrated and described herein with more or less particularity but it is to be expressly understood that said invention is not 40 limited to said embodiments or otherwise than by the terms of the appended claims.

What is claimed is:—

1. In a folding machine, a vertical bank or series of horizontal feeding and folding rollers and a plurality of horizontal fold plates associated with said bank or series alternately upon opposite sides thereof, a vertical frame disposed below the rollers and said fold plates and having horizontal guide means and vertical guide means for a series of separate folded sheet sections delivered 45 downwardly through the latter to stand on their lower edges on the horizontal guide means, cutting mechanism mounted on the vertical frame and comprising a plurality of spaced cutters rotatable on a horizontal axis and adapted to form 50 the series of separate sheet sections from a folded sheet delivered to said cutters through certain of said rollers, a cross fold mechanism adjacent one end of the horizontal guide means and comprising 55 a vertical fold plate and similarly disposed feeding and folding rollers associated therewith, and cross feed devices arranged on the horizontal guide means in two opposed rows extending therealong substantially throughout the length thereof, said cross feed devices being adapted to engage the 60 lower edge portions of the series of folded sheet sections on both sides of each section and feed said sections one after another in standing position along said horizontal guide means and through said vertical guide means to said cross fold mechanism.

2. In a folding machine, a bank of horizontal feeding and folding rollers extending one above another and a plurality of fold plates associated therewith, a plurality of spaced cutters positioned adjacent said bank, said cutters being rotatable on

a substantially horizontal axis and adapted to form a series of separate sheet sections from a sheet delivered thereto through certain of said rollers, a horizontal guide disposed below the cutters and onto which the series of sheet sections are delivered to stand on their lower edges thereon along the same, a cross fold mechanism adjacent one end of the horizontal guide and comprising a vertical fold plate and similarly disposed feeding and folding rollers associated therewith, and cross feed devices arranged on the horizontal guide in two opposed rows extending therealong substantially throughout the length thereof, said cross feed devices being adapted to engage the lower edge portions of the series of sheet sections on both sides of each of the same and feed said sections one after another in standing position along said guide to said cross fold mechanism.

3. In a folding machine, a series of horizontal feeding and folding rollers and one or more fold plates associated therewith, means adjacent said series for cutting separate sections from a sheet delivered thereto through certain of said rollers, a horizontal guide disposed below the cutting means and onto which the sheet sections are delivered to stand on their lower edges thereon along the same, a cross fold mechanism adjacent one end of the guide and comprising a fold plate and feeding and folding rollers associated therewith at right angles to said first named rollers, and cross feed devices arranged in two opposed rows substantially parallel with the horizontal guide and extending substantially throughout the length thereof, said cross feed devices being adapted to engage the lower edge portions of the sheet sections on both sides of each of the same and feed said sections one after another in standing position along said guide to said cross fold mechanism.

4. In a folding machine, horizontally disposed mechanism for making parallel folds in sheet material, means adjacent said mechanism for cutting separate sections from a sheet delivered therefrom, a horizontal guide disposed below said means and onto which the sheet sections are delivered 45 downwardly to stand on their lower edges, a cross fold mechanism mounted adjacent one end of the guide at right angles to said first named mechanism, and cross feed devices arranged in two opposed rows substantially parallel with the horizontal guide and extending substantially throughout the length thereof, said cross feed devices being adapted to engage the lower edge portions of the sheet sections on both sides of each of the same and feed said sections one after another in standing position along said guide to said cross fold mechanism.

5. In a folding machine, a plurality of means rotatable about a substantially horizontal axis and adapted to cut a sheet into a series of separate sections, a substantially horizontal guide disposed below said plurality of means and onto which the sheet sections are delivered to stand on their lower edges thereon, folding mechanism adjacent one end of the guide, and cross feed devices arranged in two opposed rows substantially parallel with the guide and extending therealong substantially throughout the length thereof, said cross feed devices being adapted to engage the lower edge portions of the series of sheet sections on both sides of each of the same and feed said sections one after another in standing position along said guide to said folding mechanism.

6. In a folding machine, means for making one

75

- or more folds in a sheet and comprising relatively displaceable sets of horizontal feeding and folding rollers and at least one fold plate associated with the rollers of each set, a plurality of spaced cutters rotatable on a horizontal axis and adapted to cut the sheet into a series of separate sections, a vertical frame carrying the cutters adjacent the top thereof and adjustable for positioning of said cutters opposite different sets of rollers to receive the sheets therefrom, a horizontal guide adjustable with and relative to the frame and mounted thereon below the cutters in spaced relation therewith, means on the frame for directing the series of sheet sections downwardly therethrough to stand on their lower edges on the horizontal guide, a cross fold mechanism adjacent one end of the guide and comprising a fold plate and a set of feeding and folding rollers associated therewith at right angles to said first named rollers, and cross feed devices arranged on the horizontal guide in two opposed rows extending therewith substantially throughout the length thereof, said cross feed devices being adapted to engage the lower edge portions of the series of sheet sections on both sides of each section and feed said sections one after another in standing position along said horizontal guide and through said frame to said cross fold mechanism.
7. In a folding machine, means for making one or more folds in a sheet and comprising relatively displaceable sets of parallel feeding and folding rollers and one or more fold plates associated with the rollers of each set, cutting means rotatable on an axis parallel with the rollers and adapted to cut the sheet into a plurality of separate sections, a guide parallel with and spaced from said axis, a movable frame carrying the cutting means and the guide and providing therewith a unit adjustable for positioning of said cutting means opposite different sets of said rollers to receive the sheet therefrom, means on the frame for directing the separate sheet sections to the guide and retaining them in position along the same, a cross fold mechanism adjacent one end of the guide and comprising a fold plate and a set of feeding and folding rollers associated therewith at right angles to said first named rollers, and means for feeding the separate sheet sections one after another along said guide and through said frame to said cross fold mechanism.
8. In a folding machine, folding means for making one or more folds in a sheet and comprising relatively displaceable sets of folding devices, a guide disposed in spaced relation with the folding means, cutting means interposed between said folding means and the guide and adapted to cut the sheet into separate sections that are delivered to the guide, movable means carrying the cutting means and the guide and providing therewith a unit adjustable to receive the sheet from different sets of said folding devices, cross folding means adjacent one end of the guide, and means for feeding said sheet sections one after another along said guide to said cross folding means.
9. In a folding machine, folding means for making one or more folds in a sheet and comprising relatively displaceable sets of folding devices, cutting means adapted to cut the sheet into separate sections, movable means carrying the cutting means for positioning the latter in operative relation with different sets of said folding devices to receive the sheet therefrom, a guide to which the sheet sections are delivered, cross folding means adjacent one end of the guide, and means for feeding said sheet sections along said guide to said cross folding means.
10. In a folding machine, folding means for making one or more folds in a sheet and comprising relatively displaceable sets of folding devices, and cutting means and feeding means adjustable as a unit with respect to said folding means to receive the sheet selectively from different sets of devices thereof, said unit comprising means for cutting said sheet into separate sections and means for guiding and feeding said sections.
11. In a folding machine, folding means for making one or more folds in sheet material, cutting means and feeding means, and movable means carrying the cutting means and the feeding means and providing for adjustment of both of the same as a unit relative to said folding means.
12. In a folding machine, folding means for making one or more folds in sheet material, cutting means and feeding means, and movable means carrying the cutting means and the feeding means and providing for adjustment of both of the same as a unit relative to said folding means, said feeding means and said cutting means being mounted on said movable means for relative adjustment.
13. In a folding machine, horizontal means for folding a sheet and cutting it into sections, a horizontal guide therebelow, means for directing the sheet sections downwardly to the guide simultaneously and for retaining the same in standing position thereon during movement of the sheet sections along the guide, series of driven rollers for feeding the sheet sections along the guide and rotatable about axes substantially at right angles thereto, and a series of spherical elements for holding said sections in engagement with said rollers and said guide.
14. In a folding machine, means for folding a sheet, a substantially horizontal guide therebelow, means for cutting the sheet into separate sections, means for directing the sections downwardly to the guide simultaneously and for retaining said sections in standing position on the guide during movement of the same therealong, driven rollers for feeding the sections along the guide and rotatable about axes substantially at right angles thereto, and spherical elements for holding said sections in engagement with said rollers and said guide, said rollers and spherical elements being arranged in two opposed rows extending along the guide substantially throughout its length to feed and fold each of the sheet sections as aforesaid.
15. In a folding machine, means for folding a sheet and dividing it into a series of separate folded sections, a substantially horizontal guide therebelow onto which the series of folded sections are simultaneously delivered downwardly in standing position thereon, a series of substantially vertical driven rollers mounted on the guide for feeding the folded sections therealong, a series of spherical elements carried by said guide for holding the folded sections in engagement with the rollers and said guide, said rollers and spherical elements being arranged in two opposed rows extending along the guide substantially throughout its length to feed and fold each of the folded sheet sections as aforesaid, and means providing for adjustment of the guide, the rollers, and the spherical elements as a unit toward and away from said folding means.
16. In a folding machine, a substantially horizontal guide, folding means adjacent one end

thereof, means for forming and directing a plurality of sheet sections vertically to the guide simultaneously and for retaining said sections in standing position thereon during movement of the same therealong, and a series of pairs of means for feeding the sheet sections one after another in standing position along said guide to the folding means, said series extending along the guide substantially from one end to the other thereof and including a device or devices adapted to accelerate the movement of the leading sheet section to said folding means.

17. In a folding machine, folding means for making one or more folds in sheet material and comprising relatively displaceable sets of folding devices, conveying means adjustable with respect to said folding means to receive said material selectively from different sets of said folding devices, and a plurality of flared guides mounted 15 on said conveying means for adjustment with the same and with respect to each other.

18. In combination, a substantially horizontal guide along which sheets may be fed in standing position thereon, a row of substantially vertical short rollers adjacent the guide for feeding the sheets therealong as aforesaid, holders disposed 20 opposite the rollers and inclined downwardly to-

ward the same, and spherical elements mounted in the holders to coact with said rollers in the feeding of said sheets along said guide.

19. In combination, a substantially horizontal guide along which sheets may be fed in standing position thereon, a row of substantially vertical short rollers adjacent the guide for feeding the sheets therealong as aforesaid, holders disposed opposite the rollers and inclined downwardly to- 5 ward the same, spherical elements mounted in 10 the holders to coact with the rollers in the feeding of said sheets along said guide, and means for varying the inclination of said holders with respect to said rollers.

20. In combination, a vertical frame, cross feed 15 mechanism mounted on the frame and adjustable vertically thereon to different positions, and a plurality of flared guides positioned above the cross feed mechanism and mounted on said frame for adjustment thereon with respect to 20 each other.

LAWRENCE HITCHCOCK,
H. MORLEY HITCHCOCK,
C. W. HITCHCOCK,
D. B. MEACHAM,

*Executors of the Estate of Reuben Hitchcock,
Deceased.*
